COLLAPSIBLE DESK OR THE LIKE

Eldred F. Tubbs, Orchard Park, N. Y.

Application September 20, 1948, Serial No. 148,666

Term of patent 7 years

(Cl. D33—7)

To all whom it may concern:

Be it known that I, Eldred F. Tubbs, a citizen of the United States, residing at Orchard Park, in the county of Erie and State of New York, have invented a new, original, and ornamental Design for a Collapsible Desk or the like, of which the following is a specification, reference being made to the accompanying drawing, forming part thereof;

Fig. 1 is a rear perspective view of a collapsible desk or the like in collapsed condition, showing my new design;

Fig. 2 is a rear perspective view with the collapsible desk shown in its assembled condition;

Fig. 3 is a rear perspective view similar to Fig. 2 but with the top portion in partially open position, and

Fig. 4 is a front view of the collapsible desk, with the top portion in open position, showing my new design.

I claim:

The ornamental design for a collapsible desk or the like, as shown.

ELDRED F. TUBBS.
